STENCIL SCREEN AND METHOD OF MAKING
THE SAME

Charles A. Wulf, Indianapolis, Ind.

Application October 17, 1936, Serial No. 106,201

4 Claims. (Cl. 41—38.6)

An object of the invention is to provide a new and improved stencil screen, for reproducing designs accurately, and a cheap and reliable method of making the same, the stencil being of the type that is produced photographically.

Another object of the invention is to produce a very thin stencil screen from the openings in which the coloring material may be removed and form the desired design accurately.

Another object of the invention is to provide a cheap and reliable method of avoiding moiré effects.

Another object of the invention is to increase the accuracy and reliability with which intermediate shades of a design may be reproduced by use of a screen stencil of proper character.

Other objects and details of the invention will appear as the description proceeds.

In the accompanying drawing, which forms a part of this specification, Figure 1 is a diagrammatic view of the photographic production of a design upon a stencil screen; Fig. 2 is an enlarged detail section of a portion of a wire screen suitable for use in making a stencil; Fig. 3 is a view similar to Fig. 2 but showing the screen flattened or ironed to reduce its thickness; Fig. 4 is a plan of a portion of the screen shown in section in Fig. 3; Fig. 5 is a diagrammatic enlarged detail illustrating the action of light on the stencil screen; Fig. 6 is a view of the finished screen portion resulting from the action shown in Fig. 5; and Fig. 7 is an enlarged plan of a more extensive portion of a screen as actually formed in accordance with this invention.

In Fig. 1 there is shown one conventional arrangement by which stencil screen patterns are produced photographically. In this view, there is a half tone transparency 10 having thereon a positive of the pattern to be reproduced. Light is passed through this transparency and falls upon the light-sensitive material of stencil screen 12.

It will be understood that the light pattern may be produced in any desired way, the essential feature of the invention in this respect being the relation of the half-tone light screen to the stencil screen, as will be described below. Light renders insoluble the light-sensitive material sufficiently exposed thereto. After the desired exposure, the stencil is soaked and washed to remove the light-sensitive material not affected by the light thus leaving portions of the screen open. Design-forming material is pressed through these openings to form the desired pattern upon a chosen surface.

The process thus far described has been in prior use, and the present invention resides in details which constitute new and valuable improvements in the general process outlined above.

Wire of silk stencil screen may be used, but

wire screen is preferred. Fig. 2 shows a detail section of wire screen readily available commercially, and hitherto considered suitable for use as a stencil screen. As shown in Fig. 2, the wires 13 and 14 cross each other and so make the screen twice as thick as the diameter of the wire from which it is made. When such a screen is used, the coloring matter within an opening through the screen has a thickness of twice the diameter of the wire. When ink is squeezed into a mesh of such a stencil screen and removed upon a surface on which the design is to be formed, the ink constitutes a pile or pyramid that is so tall in proportion to its base that it is likely to run and spread, unless the ink or design-forming material is quite stiff.

The preferred way of avoiding this difficulty, is to iron the screen or run it through rollers to flatten it in the manner shown in Fig. 3. The wires 13 and 14 are flattened at 15 on the outside of each intersection. As a result the thickness of the screen is reduced to but little more than that of a single wire. The blob of coloring matter transmitted through such an opening is of less height in proportion to its base, and is removed from the opening more easily and cleanly. The base of the blob in proportion to its height is relatively increased so that there is much less running or spreading of the pigment after deposit on the receiving surface. As a consequence there is much less coalescing of the individual deposits on the receiving surfaces before complete setting of the pigment.

A somewhat similar effect might be produced by punching holes in a thin sheet, or by weaving flattened wires or ribbons in place of the usual round wires, but obviously any such method of producing the screen would be much more costly than merely ironing or flattening a wire screen available on the market.

In Fig. 5, the light action on the light-sensitive filler of the screen is indicated. It will be readily understood that the openings between wires 13 and 14 are filled with light-sensitive material in the usual manner. The relative position of the lines of the usual light screen, employed in making pattern 10, is indicated by heavy dotted lines 17, and it will be readily understood that the stencil-forming light falls in spots in the centers of the squares outlined by lines 17.

As indicated in Fig. 5, the meshes of the stencil screen are much finer than those of the light screen. A suitable proportion to use is ninety lines to the inch on the light screen and two hundred and fifty wires to the inch in the stencil screen. Two good results are obtained by employing a much finer mesh in the stencil than in the light screen.

Moiré effect is one of the recognized difficulties encountered in this process. This is lessened by

the use of a relatively fine-mesh stencil screen. Moiré effect has been found to occur when 200 mesh wire stencil has been used with 90 line light screen; but when the same light screen has been used with 250 wire stencil screen, moiré effect has been greatly reduced. Therefore, a proportion of at least $2\frac{1}{2}$ to 1 between the meshes of the stencil and light screen is considered critical in substantially eliminating moiré effects. When 10 the stencil has at least $2\frac{1}{2}$ times as many meshes each way as the light screen, it has at least six times as many meshes in a given area.

The relatively fine mesh of the stencil screen also aids greatly in producing accurately shaded 15 designs, particularly in reproducing wood grain and marble designs, where the grain and lines are indicated largely by different shades of the same color.

In Fig. 5, there are indicated, for purposes of 20 illustration, three light-affected spots 20, 21 and 22 of different diameters, in accordance with the amount of the light transmitted to the respective points. As indicated above, the design on the 25 stencil is produced by the hardening by light of the material in meshes subjected to the light, whereas the material insufficiently affected by light is washed out of the stencil screen, leaving openings through which coloring material may be forced. As will be seen from Fig. 6, the effect 30 of the three light-affected spots 20, 21 and 22 is to leave in the finished screen different numbers of screen meshes plugged with the hardened material. It is evident that the hardened material will be washed off with the dissolved material 35 except where the hardened material extends to the wires, and that where only a flap of hardened material is left, attached to a wire on one side, it is readily brushed off, and even if it clings to the wire until the first use of the stencil, the coloring matter pushes it aside. Consequently, the light-hardened material is effective in pattern-forming 40 only when it clings to at least two wires and the meshes of the final stencil are either completely open, completely closed, or sometimes half closed. 45 When the stencil mesh is about the same size as the light-screen mesh so that there is one light beam for each mesh of the stencil screen, most of the stencil meshes remain entirely open in the less affected portions of the stencil and 50 entirely closed in the more affected portions. The result is that the reproduced design has less fine shading and more abrupt and sharp contacts than the original. As will be seen from Fig. 6, the relatively fine stencil screen makes possible the 55 gradual increase in the number of squares in which the material is sufficiently hardened to remain, as the amount of light is increased. Where the maximum spread of a light dot is only one mesh, it can only leave the mesh open, closed, or 60 half closed, making possible but three alternatives. Where a light dot may spread over eight or nine meshes, there is a possible variation of from one-half mesh by half-mesh stages up to the maximum of eight or nine meshes, making 65 possible a very gradual shading from light to dark.

A fine-meshed stencil screen made in this improved way has a multiplicity of spots of light-hardened material thereon, each spot covering 70 from one-half a mesh up to a plurality of meshes, and is thus distinguished from a screen where each light dot affected only one mesh.

Fig. 7 is a reproduction of an enlarged view of a small section of a screen produced in the manner described. In this view it will be seen that the areas affected by the light beams vary from $1\frac{1}{2}$ meshes to four meshes of the screen. It will be readily seen that a similar gradual variation will extend to an area on the one hand where all meshes are filled to an area on the other hand where all are open.

The commercial fine-meshed screen is made 10 of finer wire than coarser screen, and the flattening of the screen as shown in Figs. 3 and 4 further reduces the effective thickness of the blob of material deposited by each open mesh. Also 15 the flattened screen provides a more nearly continuous margin for each mesh and adds to the reliability with which the light hardened material remains attached to the wire, and therefore cooperates with the relatively fine-meshed effect to 20 produce very accurate reproductions of designs comprising different shadings.

While, as will be noted by comparing Figs. 5 and 6, some of the hardened material may be lost from each of spots 20, 21 and 22, so that the reproduction is not microscopically accurate, no 25 dot of any appreciable size is entirely lost, and the loss on different dots so nearly evens up on the average that any difference between the original half tone design and the final design applied by the stencil is not noticeable to the naked 30 eye.

As indicated above, this invention is peculiarly effective when employed to reproduce wood graining or marbling, but it will be readily understood that it may be employed for other purposes where 35 similar effects are desired, and that departures, obvious to those skilled in the art, may be made from the exact process, proportions and construction disclosed; within the terms of the appended 40 claims.

What I claim is:

1. A stencil screen comprising open-meshed woven round wire flattened at the intersections and certain of the meshes being closed to form a desired design.

2. A stencil screen comprising open-meshed woven round wire flattened at the intersections and having spots of light hardened material thereon, said spots varying from not more than one mesh to at least three meshes in extent, 50 whereby a gradually shaded design may be produced.

3. A stencil screen comprising open-meshed woven round wire flattened at the intersections and having spots of light hardened material 55 thereon, said spots varying from not more than one mesh to at least six meshes in extent, whereby a gradually shaded design may be produced.

4. A method of forming a stencil screen from fine meshed woven wire, which consists in flattening the intersections of the wires, filling the openings of the meshes with a soluble material capable of being rendered insoluble by light, passing light, in a half tone pattern materially coarser than the wire meshes, onto said material 65 and thereby rendering portions of said material insoluble in a pattern corresponding with said light pattern, and then washing away the still soluble portion of said material.

CHARLES A. WULF.
